(57) **ABSTRACT**

A sole structure for an article of footwear includes a chassis having a first side defining a footbed and a second side disposed on an opposite side from the first side, a first bladder attached to the second side of the chassis and including at least one first chamber defining a first polar axis oriented in a first direction, and a second bladder attached to second side of the chassis and including at least one second chamber defining a second polar axis oriented in a second direction transverse to the first direction.

SOLE STRUCTURE FOR ARTICLE OF FOOTWEAR

CROSS REFERENCE TO RELATED APPLICATIONS

This application claims priority under 35 U.S.C. § 119(e) to U.S. Provisional Application 63/174,659, filed on Feb. 14, 2021. The disclosure of this prior application is considered part of the disclosure of this application and is hereby incorporated by reference in its entirety.

FIELD

The present disclosure relates generally to methods and systems for forming bladders for articles of footwear, and to sole structures incorporating bladders formed using the methods and systems.

BACKGROUND

This section provides background information related to the present disclosure, which is not necessarily prior art.

Articles of footwear conventionally include an upper and a sole structure. The upper may be formed from any suitable material(s) to receive, secure, and support a foot on the sole structure. The upper may cooperate with laces, straps, or other fasteners to adjust the fit of the upper around the foot. A bottom portion of the upper, proximate to a bottom surface of the foot, attaches to the sole structure.

Sole structures generally include a layered arrangement extending between a ground surface and the upper. One layer of the sole structure includes an outsole that provides traction with the ground surface. The outsole may be formed from rubber or other materials that impart durability and wear-resistance, as well as enhance traction with the ground surface. Another layer of the sole structure includes a midsole disposed between the outsole and the upper. The midsole provides cushioning for the foot and may be partially formed from a polymer foam material that compresses resiliently under an applied load to cushion the foot by attenuating ground-reaction forces. The midsole may additionally or alternatively incorporate a fluid-filled bladder to provide cushioning to the foot by compressing resiliently under an applied load to attenuate ground-reaction forces. Sole structures may also include a comfort-enhancing insole or a sockliner located within a void proximate to the bottom portion of the upper and a stropel attached to the upper and disposed between the midsole and the insole or sockliner.

Midsoles employing bladders typically include a bladder formed from two barrier layers of polymer material that are sealed or bonded together. The bladders may contain air, and are designed with an emphasis on balancing support for the foot and cushioning characteristics that relate to responsiveness as the bladder resiliently compresses under an applied load.

DRAWINGS

The drawings described herein are for illustrative purposes only of selected configurations and are not intended to limit the scope of the present disclosure.

FIG. 1 is a bottom perspective view of an article of footwear including a sole structure formed according to the principles of the present disclosure;

FIG. 2 is a top perspective view of the sole structure of FIG. 1;

FIG. 3 is an exploded top perspective view of the sole structure of FIG. 1;

FIG. 3A is an exploded top perspective view of the sole structure of FIG. 1 showing the first bladder and the second bladder formed as separate pieces;

FIG. 4 is an exploded bottom perspective view of the sole structure of FIG. 1;

FIG. 4A is an exploded bottom perspective view of the sole structure of FIG. 1 showing the first bladder and the second bladder formed as separate pieces;

FIG. 5 a bottom plan view of the sole structure of FIG. 1;

FIG. 5A a bottom plan view of the sole structure of FIG. 1 showing the first bladder and the second bladder formed as separate pieces;

FIG. 6A is a cross-sectional view of the sole structure of FIG. 1, taken along Line 6A-6A in FIG. 5;

FIG. 6B is a cross-sectional view of a second aspect of the sole structure of FIG. 1, taken along Line 6B-6B in FIG. 5A;

FIG. 7A is a cross-sectional view of the sole structure of FIG. 1, taken along Line 7-7 in FIG. 5;

FIG. 7B is a cross-sectional view of a second aspect of the sole structure of FIG. 1, taken along Line 7B-7B in FIG. 5A;

FIG. 8 is a cross-sectional view of the sole structure of FIG. 1, taken along Line 8-8 in FIG. 5;

FIGS. 9A and 9B are plan views of mold plates of a molding system for forming a bladder of a sole structure according to the principles of the present disclosure; and

FIGS. 10A-10D are schematic views of a mold system including the mold plates of FIGS. 9A and 9B, showing a method of using the mold system to form a bladder according to the principles of the present disclosure.

Corresponding reference numerals indicate corresponding parts throughout the drawings.

DETAILED DESCRIPTION

Example configurations will now be described more fully with reference to the accompanying drawings. Example configurations are provided so that this disclosure will be thorough, and will fully convey the scope of the disclosure to those of ordinary skill in the art. Specific details are set forth such as examples of specific components, devices, and methods, to provide a thorough understanding of configurations of the present disclosure. It will be apparent to those of ordinary skill in the art that specific details need not be employed, that example configurations may be embodied in many different forms, and that the specific details and the example configurations should not be construed to limit the scope of the disclosure.

The terminology used herein is for the purpose of describing particular exemplary configurations only and is not intended to be limiting. As used herein, the singular articles “a,” “an,” and “the” may be intended to include the plural forms as well, unless the context clearly indicates otherwise.

The terms “comprises,” “comprising,” “including,” and “having,” are inclusive and therefore specify the presence of features, steps, operations, elements, and/or components, but do not preclude the presence or addition of one or more other features, steps, operations, elements, components, and/or groups thereof. The method steps, processes, and operations described herein are not to be construed as necessarily requiring their performance in the particular order discussed or illustrated, unless specifically identified as an order of performance. Additional or alternative steps may be employed.

When an element or layer is referred to as being “on,” “engaged to,” “connected to,” “attached to,” or “coupled to”

another element or layer, it may be directly on, engaged, connected, attached, or coupled to the other element or layer, or intervening elements or layers may be present. In contrast, when an element is referred to as being "directly on," "directly engaged to," "directly connected to," "directly attached to," or "directly coupled to" another element or layer, there may be no intervening elements or layers present. Other words used to describe the relationship between elements should be interpreted in a like fashion (e.g., "between" versus "directly between," "adjacent" versus "directly adjacent," etc.). As used herein, the term "and/or" includes any and all combinations of one or more of the associated listed items.

The terms first, second, third, etc. may be used herein to describe various elements, components, regions, layers and/or sections. These elements, components, regions, layers and/or sections should not be limited by these terms. These terms may be only used to distinguish one element, component, region, layer or section from another region, layer or section. Terms such as "first," "second," and other numerical terms do not imply a sequence or order unless clearly indicated by the context. Thus, a first element, component, region, layer or section discussed below could be termed a second element, component, region, layer or section without departing from the teachings of the example configurations.

In one configuration, a sole structure for an article of footwear includes a chassis having a first side defining a footbed and a second side disposed on an opposite side from the first side, a first bladder attached to the second side of the chassis and including at least one first chamber defining a first polar axis oriented in a first direction, and a second bladder attached to second side of the chassis and including at least one second chamber defining a second polar axis oriented in a second direction transverse to the first direction.

The sole structure may include one or more of the following optional features. For example, the first direction may be a first oblique angle oriented towards a lateral side of the sole structure and the second direction may be a second oblique angle oriented towards a medial side of the sole structure. Additionally or alternatively, the at least one first chamber may be aligned with the at least one second chamber in a lateral direction of the sole structure and/or the at least one first chamber and the at least one second chamber may each have an ellipsoidal shape. Further, the ellipsoidal shape may be truncated.

At least one first chamber may include a plurality of first chambers arranged along a lateral side of the sole structure and the at least one second chamber may include a plurality of second chambers arranged along a medial side of the sole structure, each of the first chambers may be oriented in the first direction and each of the second chambers may be oriented in the second direction.

In one configuration, the second side of the chassis may include at least one first socket attached to the at least one first chamber and at least one second socket attached to the at least one second chamber. The at least one first socket may be oriented in the first direction and the at least one second socket may be oriented in the second direction. The at least one first socket may include a first receptacle configured to receive the at least one first chamber and the at least one second socket may include a second receptacle configured to receive the at least one second chamber. The first receptacle may define a first concave surface and the second receptacle may define a second concave surface.

In one configuration, the first bladder and the second bladder are a unitary piece. Alternatively, the first bladder and the second bladder are separate from one another.

In another configuration, a sole structure for an article of footwear includes a chassis having a top side defining a footbed and a bottom side disposed on an opposite side from the top side, a first bladder attached to the chassis at the bottom side and including at least one first chamber distended beyond the footbed on a first side of the sole structure, and a second bladder attached to the chassis at the bottom side and including at least one second chamber distended beyond the footbed on a second side of the sole structure.

The sole structure may include one or more of the following optional features. For example, the at least one first chamber may extend at a first oblique angle oriented towards the first side of the sole structure and the at least one second chamber may extend at a second oblique angle oriented towards the second side of the sole structure. The at least one first chamber may be aligned with the at least one second chamber in a lateral direction of the sole structure. Additionally or alternatively, the at least one first chamber and the at least one second chamber may each have an ellipsoidal shape. The ellipsoidal shape may be truncated.

In one configuration, the at least one first chamber may include a plurality of first chambers arranged along a lateral side of the sole structure and the at least one second chamber may include a plurality of second chambers arranged along a medial side of the sole structure, each of the first chambers may be oriented in a first direction and each of the second chambers may be oriented in a second direction.

The bottom side of the chassis may include at least one first socket attached to the at least one first chamber and at least one second socket attached to the at least one second chamber. The at least one first socket may be oriented towards the first side of the sole structure and the at least one second socket may be oriented towards the second side of the sole structure. Additionally or alternatively, the at least one first socket may include a first receptacle configured to receive the at least one first chamber and the second socket may include a second receptacle configured to receive the at least one second chamber. The first receptacle may define a first concave surface and the second receptacle may define a second concave surface.

In one configuration, the first bladder and the second bladder are a unitary piece. Alternatively, the first bladder and the second bladder are separate from one another.

In another configuration, a method of forming a sole structure for an article of footwear includes (i) inserting a barrier layer in a mold cavity of a mold assembly, the mold cavity defining at least one first chamber cavity oriented at a first angle and at least one second chamber cavity oriented at a second angle, (ii) biasing the barrier layer against a surface of the mold cavity to form a cushioning arrangement including at least one first chamber in the at least one first chamber cavity oriented at the first angle and at least one second chamber in the at least one second chamber cavity oriented at the second angle; (iii) extracting the cushioning arrangement from the mold cavity, (iv) rotating the first chamber in a first direction about a longitudinal axis of the cushioning arrangement to orient the first chamber at a third angle, and (v) rotating the second chamber in a second direction about the longitudinal axis to orient the second chamber at a fourth angle transverse to the third angle.

The method may include one or more of the following optional steps and features. For example, the method may include attaching the first chamber to a first socket of a

chassis oriented at the third angle and/or attaching the second chamber to a second socket of the chassis oriented at the fourth angle. Orienting the at least one first chamber at the third angle may include positioning a lower portion of the at least one first chamber outwardly from an upper portion of the first chamber relative to a longitudinal axis of the sole structure. The at least one first chamber cavity may include a plurality of first chamber cavities and the at least one second chamber cavity may include a plurality of second chamber cavities.

In one configuration, biasing the barrier layer against the surface of the mold cavity may include providing a fluid to the plurality of first chamber cavities via a first inflation conduit and providing a fluid to the plurality of second chamber cavities via a second inflation conduit in parallel with the first inflation conduit. Additionally or alternatively, the method may include joining the barrier layers together at a first inflation port to seal the at least one first chamber and joining the barrier layers together at a second inflation port to seal the at least one second chamber in fluid isolation from the at least one first chamber.

The mold cavity may define a ridge disposed between the at least one first chamber cavity and the at least one second chamber cavity. The ridge may include a first ridge surface adjacent to the at least one first chamber cavity and a second ridge surface adjacent to the at least one second chamber cavity, the first ridge surface may be transverse to the second ridge surface. In one configuration, a width of the ridge may taper between the first chamber cavity and the second chamber cavity.

The method may additionally include forming a gap between the at least one first chamber and the at least one second chamber using the ridge, and bending the at least one first chamber towards the at least one second chamber to reduce a width of the gap.

A mold system for forming a cushioning arrangement for an article of footwear includes at least one first chamber cavity oriented at a first angle, at least one second chamber cavity oriented at a second angle transverse to the first angle, an inflation manifold including a first inflation conduit in fluid communication with the at least one first chamber cavity and a second inflation conduit in fluid communication with the at least one second chamber cavity.

The mold system may include one or more of the following optional features. For example, the at least one first chamber cavity may include a plurality of chamber cavities fluidly coupled along the first inflation conduit and the at least one second chamber cavity may include a plurality of second chamber cavities fluidly coupled along the second inflation conduit. The at least one first chamber cavity may have a first ellipsoidal shape defining a first axis oriented at the first angle and the at least one second chamber cavity may have a second ellipsoidal shape defining a second axis oriented at the second angle. At least one of the first ellipsoidal shape or the second ellipsoidal shape may include a truncated ellipsoidal shape.

In one configuration, a ridge may be disposed between the at least one first chamber cavity and the at least one second chamber cavity. The ridge may include a first ridge surface adjacent to the at least one first chamber cavity and a second ridge surface adjacent to the at least one second chamber cavity, the first ridge surface may be transverse to the second ridge surface. Additionally or alternatively, a width of the ridge may taper between the first chamber cavity and the second chamber cavity.

The details of one or more implementations of the disclosure are set forth in the accompanying drawings and the

description below. Other aspects, features, and advantages will be apparent from the description and drawings, and from the claims.

Referring to FIG. 1, an article of footwear 10 includes a sole structure 100 and an upper 200 attached to the sole structure 100. The footwear 10 may further include an anterior end 12 associated with a forward-most point of the footwear 10, and a posterior end 14 corresponding to a rearward-most point of the footwear 10. As shown in FIGS. 5 and 5A, a longitudinal axis A₁₀ of the footwear 10 extends along a length of the footwear 10 from the anterior end 12 to the posterior end 14 parallel to a ground contacting plane P₁₀₀ (shown in FIGS. 6A and 6B) defined by the sole structure 100, and generally divides the footwear 10 into a lateral side 16 and a medial side 18. Accordingly, the lateral side 16 and the medial side 18 respectively correspond with opposite sides of the footwear 10 and extend from the anterior end 12 to the posterior end 14. As used herein, a longitudinal direction refers to the direction extending from the anterior end 12 to the posterior end 14, while a lateral direction refers to the direction transverse to the longitudinal direction and extending from the lateral side 16 to the medial side 18. Furthermore, a vertical direction refers to the direction extending from the ground-contacting plane P₁₀₀ towards the upper 200.

The article of footwear 10 may be divided into one or more regions. The regions may include a forefoot region 20, a mid-foot region 22, and a heel region 24. The forefoot region 20 may be subdivided into a toe portion 20T corresponding with phalanges and a ball portion 20B associated with metatarsal bones of a foot. The mid-foot region 22 may correspond with an arch area of the foot, and the heel region 24 may correspond with rear portions of the foot, including a calcaneus bone.

With reference to FIGS. 1 and 2, the sole structure 100 includes a midsole 102 configured to provide cushioning characteristics to the sole structure 100, and an outsole 104 configured to provide a ground-engaging surface of the article of footwear 10. Unlike conventional sole structures, the midsole 102 of the sole structure 100 may be formed compositely and include a plurality of subcomponents for providing desired forms of cushioning and support throughout the sole structure 100. For example, the midsole 102 includes a chassis 106 extending from the anterior end 12 to the posterior end 14 and a cushioning arrangement 108 attached to the chassis 106. The chassis 106 is configured to be attached to the upper 200 and provides an interface between the upper 200 and the cushioning arrangement 108. In the illustrated example, the cushioning arrangement 108 includes a first bladder 110 extending along the lateral side 16 and a second bladder 112 extending along the medial side 18. As described in greater detail below, the first bladder 110 includes a plurality of first chambers 114a-114g and the second bladder 112 includes a plurality of second chambers 116a-116g.

With reference to FIGS. 1-4A, the chassis 106 of the midsole 102 extends continuously from a first end 118 at the anterior end 12 to a second end 120 at the posterior end 14. The chassis 106 includes a top side 122 defining a footbed 60 of the sole structure 100 and a bottom side 124 formed on an opposite side from the top side 122. A peripheral side surface 126 of the chassis 106 extends between the top side 122 and the bottom side 124 and defines an outer peripheral profile of the chassis 106 and the footbed.

As best shown in FIGS. 4 and 4A, the bottom side 124 of the chassis 106 includes a plurality of sockets 128a-128g, 130a-130g arranged along the length of the chassis 106 from

the first end 118 to the second end 120. As discussed in greater detail below, the sockets 128a-128g, 130a-130g are configured to receive corresponding ones of the chambers 114a-114g, 116a-116g of the cushioning arrangement 108. In the illustrated example, the chassis 106 includes a plurality of first sockets 128a-128g arranged in series along the lateral side 16 of the chassis 106 from the first end 118 to the second end 120. The chassis 106 further includes a plurality of second sockets 130a-130g arranged in series along the medial side 18 of the chassis 106 from the first end 118 to the second end 120. Each one of the first sockets 128a-128g on the lateral side 16 is aligned along the lateral direction of the sole structure 100 with a respective one of the second sockets 130a-130g on the medial side 18. In other words, the first sockets 128a-128g and the second sockets 130a-130g cooperate with each other to define rows of the sockets 128a-128g, 130a-130g along the length of the sole structure 100.

Each of the first sockets 128a-128g and the second sockets 130a-130g includes a receptacle 132a-132g, 134a-134g formed at a distal end of the socket 128a-128g, 130a-130g. The receptacles 132a-132g, 134a-134g are configured to interface with respective ones of the chambers 114a-114g, 116a-116g to secure a position and orientation of the chamber 114a-114g, 116a-116g relative to the chassis 106. In the illustrated example, the receptacles 132a-132g, 134a-134g are each defined by a concave surface configured to mate with a corresponding convex surface of one of the chambers 114a-114g, 116a-116g.

With reference to FIGS. 6A and 6B, a cross-sectional view of the sole structure 100 shows a row including a first socket 128e of the chassis 106 and associated with the first bladder 110 and a respective second socket 130e of the chassis 106 and associated with the second bladder 112. While the sizes and shapes of the sockets 128a-128g, 130a-130g of the chassis 106 may differ, it will be appreciated that the features described herein with respect to the sockets 128e, 130e are common among all of the sockets 128a-128g, 130a-130g such that the remaining sockets are not individually shown and described. As shown in FIGS. 6A and 6B, the first receptacle 132e of the first socket 128e and the second receptacle 134e of the second socket 130e are oriented in opposite directions away from the longitudinal axis A₁₀. In other words, the first receptacle 132e disposed along the lateral side 16 of the chassis 106 is oriented towards the lateral side 16 at a first oblique angle θ₁₃₂ relative to the ground-contacting plane P₁₀₀ and the second receptacle 134e disposed along the medial side 18 of the chassis 106 is oriented towards the medial side 18 at a second oblique angle θ₁₃₄ relative to the ground-contacting plane P₁₀₀. Here, the first oblique angle θ₁₃₂ and the second oblique angle θ₁₃₄ are transverse to each other, such that axes A₁₃₂, A₁₃₄ extending normal to the surfaces defining the receptacles 132e, 134e converge with each other in a direction extending away from the ground-contacting plane P₁₀₀.

The first oblique angle θ₁₃₂ and the second oblique angle θ₁₃₄ may be the same (i.e., equal angles in opposite directions) for each receptacle 132e, 134e in a row. Additionally or alternatively, the receptacles 132a-132g, 134a-134g of other rows may have different values from each other. For example, and as discussed in greater detail below, receptacles 132a-132g, 134a-134g associated with portions of the sole structure 100 that are subjected to relatively high lateral forces (e.g., cutting movements) may have a greater outward orientation (i.e., smaller angles θ₁₃₂, θ₁₃₄). Conversely, receptacles 132a-132g, 134a-134g associated with portions of the sole structure 100 that are subjected to relatively high

vertical forces (e.g., jumping movements) may have a greater vertical orientation (i.e., larger angles θ₁₃₂, θ₁₃₄).

With continued reference to FIGS. 3 and 3A, the top side 122 of the chassis 106 includes one or more vents 140b-140g arranged between the first end 118 and the second end 120. In the illustrated example, the chassis 106 includes a plurality of the vents 140b-140g arranged in series from the first end 118 to the second end 120. Here, each one of the vents 140b-140g is aligned with a row of the sockets 128b-128g, 130b-130g. Each of the vents 140b-140g extends across the footbed from the lateral side 16 to the medial side 18 and includes a lattice structure defining a plurality of recesses in the top side 122. Here, the vents 140b-140g extend partially through the thickness of the chassis 106 from the top side 122. Thus, the vents 140b-140g are enclosed along the bottom side 124 of the chassis 106 to define a plurality of fluid cavities in the footbed to improve breathability within the article of footwear 10.

As shown in FIGS. 4 and 4A, the chassis 106 further includes a plurality of ribs 142 extending along the bottom side 124 in the forefoot region 20. As shown, the ribs 142 are arranged in parallel and each extend along the longitudinal direction between subsequent ones of the sockets 128b-128d, 130b-130d. The ribs 142 are configured to provide longitudinal stiffness along the ball portion 20B of forefoot region 20. In contrast, the bottom side 124 of the chassis 106 includes a continuous surface between the sockets 128a-128g, 130a-130g in the toe portion 20T, the mid-foot region 22, and heel region 24 to allow a greater degree of articulation between the sockets 128a-128g, 130a-130g.

As described above, the chassis 106 is formed of a resilient polymeric material, such as foam or rubber, to impart properties of cushioning, responsiveness, and energy distribution to the foot of the wearer. Example resilient polymeric materials for the chassis 106 may include those based on foaming or molding one or more polymers, such as one or more elastomers (e.g., thermoplastic elastomers (TPE)). The one or more polymers may include aliphatic polymers, aromatic polymers, or mixtures of both; and may include homopolymers, copolymers (including terpolymers), or mixtures of both.

In some aspects, the one or more polymers may include olefinic homopolymers, olefinic copolymers, or blends thereof. Examples of olefinic polymers include polyethylene, polypropylene, and combinations thereof. In other aspects, the one or more polymers may include one or more ethylene copolymers, such as, ethylene-vinyl acetate (EVA) copolymers, EVOH copolymers, ethylene-ethyl acrylate copolymers, ethylene-unsaturated mono-fatty acid copolymers, and combinations thereof.

In further aspects, the one or more polymers may include one or more polyacrylates, such as polyacrylic acid, esters of polyacrylic acid, polyacrylonitrile, polyacrylic acetate, polymethyl acrylate, polyethyl acrylate, polybutyl acrylate, polymethyl methacrylate, and polyvinyl acetate; including derivatives thereof, copolymers thereof, and any combinations thereof.

In yet further aspects, the one or more polymers may include one or more ionomeric polymers. In these aspects, the ionomeric polymers may include polymers with carboxylic acid functional groups, sulfonic acid functional groups, salts thereof (e.g., sodium, magnesium, potassium, etc.), and/or anhydrides thereof. For instance, the ionomeric polymer(s) may include one or more fatty acid-modified ionomeric polymers, polystyrene sulfonate, ethylene-methacrylic acid copolymers, and combinations thereof.

In further aspects, the one or more polymers may include one or more styrenic block copolymers, such as acrylonitrile butadiene styrene block copolymers, styrene acrylonitrile block copolymers, styrene ethylene butylene styrene block copolymers, styrene ethylene butadiene styrene block copolymers, styrene ethylene propylene styrene block copolymers, styrene butadiene styrene block copolymers, and combinations thereof.

In further aspects, the one or more polymers may include one or more polyamide copolymers (e.g., polyamide-polyether copolymers) and/or one or more polyurethanes (e.g., crosslinked polyurethanes and/or thermoplastic polyurethanes). Examples of suitable polyurethanes include those discussed below for the barrier layers of the bladders. Alternatively, the one or more polymers may include one or more natural and/or synthetic rubbers, such as butadiene and isoprene.

When the resilient polymeric material is a foamed polymeric material, the foamed material may be foamed using a physical blowing agent which phase transitions to a gas based on a change in temperature and/or pressure, or a chemical blowing agent which forms a gas when heated above its activation temperature. For example, the chemical blowing agent may be an azo compound such as azodicarbonamide, sodium bicarbonate, and/or an isocyanate.

In some embodiments, the foamed polymeric material may be a crosslinked foamed material. In these embodiments, a peroxide-based crosslinking agent such as dicumyl peroxide may be used. Furthermore, the foamed polymeric material may include one or more fillers such as pigments, modified or natural clays, modified or unmodified synthetic clays, talc glass fiber, powdered glass, modified or natural silica, calcium carbonate, mica, paper, wood chips, and the like.

The resilient polymeric material may be formed using a molding process. In one example, when the resilient polymeric material is a molded elastomer, the uncured elastomer (e.g., rubber) may be mixed in a Banbury mixer with an optional filler and a curing package such as a sulfur-based or peroxide-based curing package, calendered, formed into shape, placed in a mold, and vulcanized.

In another example, when the resilient polymeric material is a foamed material, the material may be foamed during a molding process, such as an injection molding process. A thermoplastic polymeric material may be melted in the barrel of an injection molding system and combined with a physical or chemical blowing agent and optionally a cross-linking agent, and then injected into a mold under conditions which activate the blowing agent, forming a molded foam.

Optionally, when the resilient polymeric material is a foamed material, the foamed material may be a compression molded foam. Compression molding may be used to alter the physical properties (e.g., density, stiffness and/or durometer) of a foam, or to alter the physical appearance of the foam (e.g., to fuse two or more pieces of foam, to shape the foam, etc.), or both.

The compression molding process desirably starts by forming one or more foam preforms, such as by injection molding and foaming a polymeric material, by forming foamed particles or beads, by cutting foamed sheet stock, and the like. The compression molded foam may then be made by placing the one or more preforms formed of foamed polymeric material(s) in a compression mold, and applying sufficient pressure to the one or more preforms to compress the one or more preforms in a closed mold. Once the mold is closed, sufficient heat and/or pressure is applied to the one or more preforms in the closed mold for a sufficient duration

of time to alter the preform(s) by forming a skin on the outer surface of the compression molded foam, fuse individual foam particles to each other, permanently increase the density of the foam(s), or any combination thereof. Following the heating and/or application of pressure, the mold is opened and the molded foam article is removed from the mold.

With continued reference to FIGS. 1 and 2, the cushioning arrangement 108 of the midsole 102 includes the first 10 bladder 110 and the second bladder 112 arranged in a side-by-side relationship along the length of the sole structure 100. Each of the bladders 110, 112 includes an interior void filled with a compressible material. As shown in the cross-sectional views of FIGS. 6A-8, each of the bladders 110, 112 may be formed by an opposing pair of barrier layers 150, 152, which can be joined to each other to form a web area 154 and a peripheral seam 156 surrounding each of the bladders 110, 112. As discussed below, the barrier layers 150, 152 include an upper barrier layer 150 and a lower barrier layer 152.

As used herein, the term "barrier layer" (e.g., barrier layers 150, 152) encompasses both monolayer and multi-layer films. In some embodiments, one or both of the barrier layers 150, 152 are each produced (e.g., thermoformed or blow molded) from a monolayer film (a single layer). In other embodiments, one or both of the barrier layers 150, 152 are each produced (e.g., thermoformed or blow molded) from a multilayer film (multiple sublayers). In either aspect, each layer or sublayer can have a film thickness ranging from about 0.2 micrometers to about 1 millimeter. In further embodiments, the film thickness for each layer or sublayer can range from about 0.5 micrometers to about 500 micrometers. In yet further embodiments, the film thickness for each layer or sublayer can range from about 1 micrometer to about 100 micrometers.

One or both of the barrier layers 150, 152 can independently be transparent, translucent, and/or opaque. As used herein, the term "transparent" for a barrier layer and/or a fluid-filled chamber means that light passes through the barrier layer in substantially straight lines and a viewer can see through the barrier layer. In comparison, for an opaque barrier layer, light does not pass through the barrier layer and one cannot see clearly through the barrier layer at all. A translucent barrier layer falls between a transparent barrier layer and an opaque barrier layer, in that light passes through a translucent layer but some of the light is scattered so that a viewer cannot see clearly through the layer.

The barrier layers 150, 152 can each be produced from an elastomeric material that includes one or more thermoplastic polymers and/or one or more cross-linkable polymers. In an aspect, the elastomeric material can include one or more thermoplastic elastomeric materials, such as one or more thermoplastic polyurethane (TPU) copolymers, one or more ethylene-vinyl alcohol (EVOH) copolymers, and the like.

As used herein, "polyurethane" refers to a copolymer (including oligomers) that contains a urethane group ($-\text{N}(\text{C}=\text{O})\text{O}-$). These polyurethanes can contain additional groups such as ester, ether, urea, allophanate, biuret, carbodiimide, oxazolidinyl, isocynaurate, uretdione, carbonate, and the like, in addition to urethane groups. In an aspect, one or more of the polyurethanes can be produced by polymerizing one or more isocyanates with one or more polyols to produce copolymer chains having ($-\text{N}(\text{C}=\text{O})\text{O}-$) linkages.

Examples of suitable isocyanates for producing the polyurethane copolymer chains include diisocyanates, such as aromatic diisocyanates, aliphatic diisocyanates, and combi-

11

nations thereof. Examples of suitable aromatic diisocyanates include toluene diisocyanate (TDI), TDI adducts with trimethyloylpropane (TMP), methylene diphenyl diisocyanate (MDI), xylene diisocyanate (XDI), tetramethylxlylylene diisocyanate (TMXDI), hydrogenated xylene diisocyanate (HXDI), naphthalene 1,5-diisocyanate (NDI), 1,5-tetrahydronaphthalene diisocyanate, para-phenylene diisocyanate (PPDI), 3,3'-dimethylidiphenyl-4, 4'-diisocyanate (DDDI), 4,4'-dibenzyl diisocyanate (DBDI), 4-chloro-1,3-phenylene diisocyanate, and combinations thereof. In some embodiments, the copolymer chains are substantially free of aromatic groups.

In particular aspects, the polyurethane polymer chains are produced from diisocynates including HMDI, TDI, MDI, H12 aliphatics, and combinations thereof. In an aspect, the thermoplastic TPU can include polyester-based TPU, polyether-based TPU, polycaprolactone-based TPU, polycarbonate-based TPU, polysiloxane-based TPU, or combinations thereof.

In another aspect, the polymeric layer can be formed of one or more of the following: EVOH copolymers, poly(vinyl chloride), polyvinylidene polymers and copolymers (e.g., polyvinylidene chloride), polyamides (e.g., amorphous polyamides), amide-based copolymers, acrylonitrile polymers (e.g., acrylonitrile-methyl acrylate copolymers), polyethylene terephthalate, polyether imides, polyacrylic imides, and other polymeric materials known to have relatively low gas transmission rates. Blends of these materials, as well as with the TPU copolymers described herein and optionally including combinations of polyimides and crystalline polymers, are also suitable.

The barrier layers 150, 152 may include two or more sublayers (multilayer film) such as shown in Mitchell et al., U.S. Pat. No. 5,713,141 and Mitchell et al., U.S. Pat. No. 5,952,065, the disclosures of which are incorporated by reference in their entireties. In embodiments where the barrier layers 150, 152 include two or more sublayers, examples of suitable multilayer films include microlayer films, such as those disclosed in Bonk et al., U.S. Pat. No. 6,582,786, which is incorporated by reference in its entirety. In further embodiments, the barrier layers 150, 152 may each independently include alternating sublayers of one or more TPU copolymer materials and one or more EVOH copolymer materials, where the total number of sublayers in each of the barrier layers 150, 152 includes at least four (4) sublayers, at least ten (10) sublayers, at least twenty (20) sublayers, at least forty (40) sublayers, and/or at least sixty (60) sublayers.

The bladders 110, 112 can be produced from the barrier layers 150, 152 using any suitable technique, such as thermoforming (e.g. vacuum thermoforming), blow molding, extrusion, injection molding, vacuum molding, rotary molding, transfer molding, pressure forming, heat sealing, casting, low-pressure casting, spin casting, reaction injection molding, radio frequency (RF) welding, and the like. In an aspect, the barrier layers 150, 152 can be produced by co-extrusion followed by vacuum thermoforming to form the profile of the cushioning arrangement 108, which can optionally include one or more valves (e.g., one way valves) that allows the cushioning arrangement 108 to be filled with the fluid (e.g., gas).

The barrier layers 150, 152 have a low gas transmission rate to preserve its retained gas pressure. In some embodiments, the barrier layers 150, 152 have a gas transmission rate for nitrogen gas that is at least about ten (10) times lower than a nitrogen gas transmission rate for a butyl rubber layer of substantially the same dimensions. In an aspect, cushion-

12

ing arrangement 108 has a nitrogen gas transmission rate of 15 cubic-centimeter/square-meter-atmosphere-day ($\text{cm}^3/\text{m}^2\cdot\text{atm}\cdot\text{day}$) or less for an average film thickness of 500 micrometers (based on thicknesses of barrier layers 150, 152). In further aspects, the transmission rate is 10 $\text{cm}^3/\text{m}^2\cdot\text{atm}\cdot\text{day}$ or less, 5 $\text{cm}^3/\text{m}^2\cdot\text{atm}\cdot\text{day}$ or less, or 1 $\text{cm}^3/\text{m}^2\cdot\text{atm}\cdot\text{day}$ or less.

As previously mentioned, the bladders 110, 112 may be generally described as including the upper barrier layer 150 configured to attach to the sockets 128a-128g, 130a-130g, and the lower barrier layer 152 configured to project from the sockets 128a-128g, 130a-130g. The barrier layers 150, 152 are joined together along the peripheral seam 156 to define an outer peripheral profile of the bladders 110, 112.

Interior surfaces of the barrier layers 150, 152 are spaced apart from each other to define an interior void filled with a compressible material. The interior voids of the bladders 110, 112 can be provided in a fluid-filled (e.g., as provided in footwear 10) or in an unfilled state. The bladders 110, 112 can be filled to include any suitable fluid, such as a gas or liquid. In an aspect, the gas can include air, nitrogen (N_2), or any other suitable gas. The fluid provided to the bladders 110, 112 can result in the bladders 110, 112 being pressurized at a pressure. In some examples, the pressure ranges from 0 psi to 25 psi, and more particularly from 5 psi to 12 psi, and even more particularly from 7 psi to 10 psi. Optionally, the bladders 110, 112 may be pressurized at different pressures. Alternatively, the fluid provided to the bladders 110, 112 can be at atmospheric pressure such that the bladders 110, 112 are not pressurized but, rather, simply contain a volume of fluid at atmospheric pressure. In other aspects, the bladders 110, 112 can alternatively include other compressible media, such as pellets, beads, ground recycled material, and the like (e.g., foamed beads and/or rubber beads).

With reference to FIGS. 1-8, each bladder 110, 112 includes a plurality of cushioning pods or chambers 114a-114g, 116a-116g connected by the web area 154. The first bladder 110 extends along the lateral side 16 of the sole structure 100 and includes a plurality of first chambers 114a-114g arranged in series between the anterior end 12 and the posterior end 14. The first chambers 114a-114g are joined together by segments of the web area 154 to form a chain-like first bladder 110 extending along the lateral side 16. Adjacent ones of the first chambers 114a-114g are fluidly connected by respective conduits 158a-158f formed in the web area 154. As shown in FIG. 4, each conduit 158a-158f extends from a posterior end of a first one of the first chambers 114a-114g to an anterior end of a second one of the first chambers 114b-114g, such that all of the first chambers 114a-114g are fluidly coupled in series.

The second bladder 112 extends along the medial side 18 of the sole structure 100 and includes a plurality of second chambers 116a-116g arranged in series between the anterior end 12 and the posterior end 14. The second chambers 116a-116g are joined together by segments of the web area 154 to form a chain-like bladder 112 extending along the medial side 18. Adjacent ones of the second chambers 116a-116g are fluidly connected by respective conduits 160a-160f formed in the web area 154. As shown in FIGS. 4 and 4A, each conduit 160a-160f extends from a posterior end of a first one of the second chambers 116a-116g to an anterior end of a second one of the second chambers 116b-116g, such that all of the second chambers 116a-116g are fluidly coupled in series.

With reference to FIG. 8, a cross sectional view of the cushioning arrangement 108 shows a profile of the second

bladder 112 and the second chambers 116a-116g. Here, a first toe chamber 116a is disposed in the toe portion 20T at the anterior end 12. A thickness T_{116a} of the toe chamber 116a tapers constantly and continuously along the direction towards the anterior end 12 to provide the toe chamber 116a with a substantially triangular cross-sectional shape. The second bladder 112 further includes a pair of forefoot chambers 116b, 116c disposed in the ball portion 20B of the sole structure 100, a pair of mid-foot chambers 116d, 116e disposed in the mid-foot region 22, and a pair of heel chambers 116f, 116g disposed in the heel region 24. The forefoot chambers 116b, 116d, the mid-foot chambers 116d, 116e, and the heel chambers 116f, 116g have an ellipsoidal cross section along the longitudinal axis. Generally, the thicknesses T_{116} (i.e., distance between upper barrier layer 150 and lower barrier layer 152) of the chambers 116a-116g increases along the direction from the anterior end 12 to the posterior end 14 such that the heel chambers 116f, 116g have a greater thickness than the mid-foot chambers 116d, 116e and the mid-foot chambers 116d, 116e have a greater thickness than the forefoot chambers 116a-116c. The first chambers 114a-114g of the first bladder 110 include a toe chamber 114a, a pair of forefoot chambers 114b, 114c, a pair of mid-foot chambers 114d, 114e, and a pair of heel chambers 114f, 114g having a substantially similar configuration to the corresponding chambers 116a-116g of the second bladder 112 shown in FIG. 8.

With reference to FIGS. 6A and 6B, a cross-sectional view taken through a row of the mid-foot chambers 114e, 116e is provided. The features shown and described with respect to the mid-foot chambers 114e, 116e are common among all chambers 114a-114g, 116a-116g except as otherwise stated herein. Each of the first chambers 114a-114g includes a first upper chamber wall 164 defined by the upper barrier layer 150 and a first lower chamber wall 166 defined by the lower barrier layer 152. The first upper chamber wall 164 defines a convex outer surface configured to interface with the corresponding concave surface of a respective one of the first receptacles 132a-132g. The first lower chamber wall 166 is generally hemispherical in shape and includes a bottom wall portion 168 defining the ground-contacting plane P_{100} and a peripheral wall portion 170 extending from the bottom wall portion 168 to the first upper chamber wall 164.

Each of the second chambers 116a-116g includes a second upper chamber wall 172 defined by the upper barrier layer 150 and a second lower chamber wall 174 defined by the lower barrier layer 152. The second upper chamber wall 172 defines a convex outer surface configured to interface with the corresponding concave surface of a respective one of the second receptacles 134a-134g. The second lower chamber wall 174 is generally hemispherical in shape and includes a bottom wall portion 176 defining the ground-contacting plane and a peripheral wall portion 178 extending from the bottom wall portion 176 to the second upper chamber wall 172.

While the upper chamber walls 164, 172 and the lower chamber walls 166, 174 are generally hemispherical in shape, the upper chamber walls 164, 172 may have a greater radius of curvature (i.e., a flatter profile) than the lower chamber walls 166, 174 to provide the chambers 114a-114g, 116a-116g with a truncated-ellipsoidal shape. Each of the first chambers 114a-114g, 116a-116g defines a polar axis A_{114}, A_{116} extending from a center point (i.e., an upper pole) of the upper chamber wall 164, 172 to a center point (i.e., a lower pole) of the lower chamber wall 166, 174. In other words, the polar axes A_{114}, A_{116} extend between the center

points or poles of the chamber walls 164, 166, 172, 174 and are generally aligned with the peripheral wall portions 170, 178 of the chambers 114a-114g, 116a-116g.

As discussed previously, the chambers 114a-114g, 116a-116g are received by respective ones of the sockets 128a-128g, 130a-130g. Specifically, the upper chamber walls 164, 172 of the chambers 114a-114g, 116a-116g interface with the receptacles 132a-132g, 134a-134g of the sockets 128a-128g, 130a-130g to position and orient the chambers 114a-114g, 116a-116g. Here, the polar axes A_{114}, A_{116} of the chambers 114a-114g, 116a-116g are coaxially aligned with the respective axes A_{132}, A_{134} such that the polar axes A_{114}, A_{116} of the chambers 114a-114g, 116a-116g are oriented at the oblique angles $\theta_{132}, \theta_{134}$ relative to the ground-contacting plane P_{100} when the sole structure 100 is assembled. As shown, the first chambers 114a-114g are oriented at the first oblique angle θ_{132} towards the lateral side 16 and ground-contacting plane and the second chambers 114a-114g are oriented at the second oblique angle θ_{134} towards the medial side 18 and ground-contacting plane P_{100} .

The angular orientations of the chambers 114a-114g, 116a-116g results in the peripheral wall portions 170, 178 being similarly oriented and projecting outwardly from the peripheral side surface 126 of the chassis 106. As shown, the peripheral wall portions 170, 178 extend outwardly from the peripheral side surface 126 on each of the lateral side 16 and the medial side 18 such that the chambers 114a-114g, 116a-116g provide the cushioning arrangement 108 with a greater width W_{108} (FIGS. 7A and 7B) than the width of the footbed. Furthermore, the angular orientation of the peripheral wall portions 170, 178 provides improved lateral stability, as lateral forces applied to the sole structure 100 are transmitted as axial forces along the length of the peripheral wall portions 170, 178 rather than pure bending forces transverse to the peripheral wall portions 170, 178.

As shown in FIGS. 3A, 4A, 5A, 6B and 7B, the first bladder 110 and the second bladder 112 are formed as independent components that are separate from one another and are separately attached to the chassis 106. FIGS. 3A and 4A show the first bladder 110 spaced apart from each other. However, when assembled to the chassis 106, the inner periphery of the first bladder 110 and the second bladder 112 may touch each other. Thus, the portion of the web area 154 connecting the first chambers 114a-114g is disconnected from the portion of the web area 154 connecting the second chambers 116a-116g. Furthermore, as discussed below, the first bladder 110 and the second bladder 112 are independently pressurized via inflation ports 180 formed in each of the heel chambers 114g, 116g (FIG. 3B). Thus, fluid pressure within the first bladder 110 may be different than the fluid pressure within the second bladder 112 during use. For example, when the first bladder 110 is compressed during a lateral movement, the pressure within the first bladder 110 may increase to a greater extent than the pressure in the second bladder 112.

FIGS. 3, 4, 5, 6A and 7A depict a cushioning arrangement 108 where the first bladder 110 and the second bladder 112 are formed as a unitary piece. The web area 154 connecting the first chambers 114a-114g is connected to the portion of the web area 154 connecting the second chambers 116a-116g. As such, the cushioning arrangement 108 may be attached to the chassis 106 as a single piece, making assembly easier relative to a cushioning arrangement 108 wherein the first bladder 110 and the second bladder 112 are formed as independent components. It should be appreciated that the connection of the first bladder 110 and the second bladder 112 allows the cushioning arrangement 108 to

15

function as a unitary piece relative to the cushioning arrangement **108** where the first bladder **110** and the second bladder **112** are formed as independent components.

The outsole **104** of the sole structure **100** extends continuously from the anterior end **12** to the posterior end **14** of the sole structure **100** and defines a ground-contacting surface of the footwear **10**. In the illustrated example, the outsole **104** is co-molded as part of the lower barrier layer **152**. In other examples, the outsole **104** may be formed separately from the cushioning arrangement **108** and attached to the lower barrier layer **152** after the cushioning arrangement is formed. Optionally, the outsole **104** may be formed as a fragmentary structure including independent fragments attached to each of the chambers **114a-114g, 116a-116g**.

The upper **200** is attached to the sole structure **100** and includes interior surfaces that define an interior void configured to receive and secure a foot for support on sole structure **100**. The upper **200** may be formed from one or more materials that are stitched or adhesively bonded together to form the interior void. Suitable materials of the upper may include, but are not limited to, mesh, textiles, foam, leather, and synthetic leather. The materials may be selected and located to impart properties of durability, air-permeability, wear-resistance, flexibility, and comfort.

Referring now to FIGS. 9A and 9B, a mold system **1000** for forming the cushioning arrangement **108** is provided. FIG. 9A shows an upper mold half **1002** and FIG. 9B shows a lower mold half **1004**. In use, the upper mold half **1002** and the lower mold half **1004** cooperate to define a mold cavity **1006** for forming the cushioning arrangement **108**. In the illustrated example, the mold system **1000** defines a pair of mold cavities **1006** for forming cushioning arrangements **108** corresponding to left and right sole structures **100**. Aside from being mirrored, the features of each of the mold cavities **1006** are the same, such that only a single mold cavity **1006** is described herein. The mold cavities **1006** are fluidly connected to each other by an inflation manifold **1008** such that the left and right cushioning arrangements **108** can be simultaneously pressurized at the same pressure.

With reference to FIG. 9A, the upper mold plate **1002** includes an upper mold surface **1010** defining a plurality of first upper chamber cavities **1012a-1012g** and a plurality of second upper chamber cavities **1014a-1014g**. The first upper chamber cavities **1012a-1012g** and the second upper chamber cavities **1014a-1014g** are configured to form a profile of the upper chamber walls **164, 172** of the chambers **114a-114g, 116a-116g**. In FIG. 9B, the lower mold plate **1004** includes a lower mold surface **1016** defining a plurality of first lower chamber cavities **1018a-1018g** and a plurality of second lower chamber cavities **1020a-1020g**. The first lower chamber cavities **1018a-1018g** and the second lower chamber cavities **1020a-1020g** are configured to form a profile of the lower chamber walls **166, 174** of the chambers **114a-114g, 116a-116g** and may also define a pattern of the outsole **104** to be co-molded with or imparted to the lower chamber walls **166, 174**.

The upper mold surface **1010** and the lower mold surface **1016** cooperate to define a ridge **1022** extending between and separating the first chamber cavities **1012a-1012g, 1018a-1018g** and the second chamber cavities **1014a-1014g, 1020a-1020g**. As discussed in greater detail below, the ridge **1022** includes a pair of ridge surfaces **1024a, 1024b** formed at an angle relative to each other. A width W_{1022} of the ridge **1022** separates the first chamber cavities

16

1012a-1012g, 1018a-1018g and the second chamber cavities **1014a-1014g, 1020a-1020g** along the length of the mold cavity **1006**.

As shown, the width W_{1022} of the ridge **1022** may be variable along the length of the mold cavity **1006**. For example, in a portion of the mold cavity **1006** including chamber cavities **1012a, 1014a, 1018a, 1020a** corresponding to the toe chambers **114a, 116a**, the width of the ridge **1022** tapers along the direction from the anterior end to the posterior end. In other words, the cavities **1012a, 1014a, 1018a, 1020a** may be splayed adjacent to the anterior end such that once the cushioning arrangement **108** is formed, the first toe chamber **114a** and the second toe chamber **116a** can be bent inwardly towards each other. As the toe chambers **114a, 116a** are bent inwardly, the toe chambers **114a, 116a** will consequently curve upwardly (i.e., away from the ground-contacting plane P_{100}) to impart a curvature along the forefoot region **20** of the cushioning arrangement **108**. Thus, the taper or splay of the ridge **1022** may be selected to tune the degree of curvature of the cushioning arrangement **108**. For example, a greater splay between the toe chambers **114a, 116a** will result in a greater curvature when the cushioning arrangement **108** is assembled.

Referring now to FIGS. 10A-10D, a cross-sectional view 25 of a generic example of a mold system **1000** according to the present disclosure is provided. Thus, the mold system **1002** includes the upper mold plate **1002**, the lower mold plate **1004**, and a portion of a mold cavity **1006** corresponding to the present disclosure is provided. Thus, the mold system **1002** includes the upper mold plate **1002**, the lower mold plate **1004**, and a portion of a mold cavity **1006** corresponding to a generic first chamber **114** and second chamber **116** of a cushioning arrangement **108**. As shown, the mold cavity **1006** includes the upper and lower first chamber cavities **1012a-1012g, 1018a-1018g** and the upper and lower second chamber cavities **1014a-1014g, 1020a-1020g** configured for forming a row including a first chamber **114** on the lateral side **16** and a second chamber **116** on the medial side **18**.

As discussed above, when the sole structure **100** is assembled, the cushioning arrangement **108** is configured so that the chambers **114, 116** are oriented outwardly at oblique angles $\theta_{132}, \theta_{134}$, whereby the peripheral wall portions **170, 178** of the chambers **114, 116** are each oriented at an oblique angle and project beyond the peripheral side surface **126** of the chassis **106**. Thus, a lower end of the peripheral wall portions **170, 178** (i.e., adjacent to the outsole **104**) is positioned outwardly from the upper end peripheral wall (i.e., adjacent to the upper chamber wall **164, 172**) when the sole structure **100** is assembled such that the outer periphery of the chambers **114, 116** is distended. Typically, mold cavities are designed with geometry corresponding to a finished geometry of the molded product and include draft angles designed to allow the molded product to be easily extracted from the mold cavity. However, forming the cushioning arrangement **108** in the finished configuration (i.e., assembled with the chassis **106**) with the distended peripheral wall portions **170, 178** would require that the corresponding chamber cavities **1012a-1012g, 1018a-1018g** include an undercut cavity wall corresponding to the distended shape of the chambers **114, 116**. An undercut wall is difficult to manufacture and presents challenges in a vacuum forming process, as the inflated chambers **114, 116** may be constricted within the undercut and, thus, difficult to extract from the mold.

With continued reference to FIG. 10A, the mold cavity **1006** of the upper mold half **1002** and the lower mold half **1004** are joined together to define chamber cavities **1026, 1028**. The chamber cavities **1026, 1028** form the distended peripheral wall portions **170, 178** of the chambers **114, 116** without using an undercut lower mold surface **1016**. Here,

polar axes A_{1026} , A_{1028} of the respective chamber cavities **1026**, **1028** are oriented inwardly at oblique angles θ_{1026} , θ_{1028} that are angularly offset from the finished orientations θ_{132} , θ_{134} of the polar axes A_{114} , A_{116} of the chambers **114**, **116**. Thus, the lower mold surface **1016** defining the lower chamber cavities **1018a-1018g**, **1020a-1020g** has a positive draft angle free of undercuts.

In a first step for forming the cushioning arrangement **108**, the upper barrier layer **150** and the lower barrier layer **152** are positioned between the mold plates **1002**, **1004** and the mold plates **1002**, **1004** are moved to the closed configuration to seal the barrier layers **150**, **152** at the respective web areas **154** and peripheral seams **156**. The barrier layers **150**, **152** may be joined together using any means for joining elastomeric materials, such as welding, thermal bonding or melding, and/or chemical adhesives, as discussed previously.

Referring to FIG. **10B**, with the barrier layers **150**, **152** joined together to form a seal, the bladders **110**, **112** are biased against the mold surfaces **1010**, **1016** to form the geometries of the bladders **110**, **112**. The barrier layers **150**, **152** may be biased against the mold surfaces **1010**, **1016** using negative pressure within the chamber cavities **1026**, **1028** (i.e., vacuum molding) and/or by introducing positive pressure within the interior void of the bladders **110**, **112** via the inflation manifold **1008**. As shown in FIGS. **9A** and **9B**, the inflation manifold **1008** may include a plurality of inflation conduits **1030** branching from an inflation header **1032** such that the bladders **110**, **112** can be simultaneously pressurized. Once the bladders **110**, **112** are formed, the inflation ports **180** of each bladder **110**, **112** may be sealed to fluidly isolate the first bladder **110** from the second bladder **112**.

Once the bladders **110**, **112** are formed within the mold cavity **1006**, the mold system **1000** is opened and the cushioning arrangement **108** is lifted from the mold cavity **1006** in an upward direction **D1**. Here, the inward orientation of the chambers **114**, **116** allows the cushioning arrangement **108** to be extracted from the mold cavity **1006** without obstruction by portion of the lower mold surface **1010** forming the lower mold cavities **1018a-1018g**, **1020a-1020g**. Upon extraction from the mold cavity **1006**, the bladders **110**, **112** may be separated from each other for installation on the chassis **106**. As shown in FIG. **10D**, the bladders **110**, **112** are rotated in an outward direction **D2** relative to the polar axes A_{1026} , A_{1028} for installation into the chassis **106** such that the peripheral wall portions **170**, **178** are distended.

The system **1000** and method of using the system **1000** to form the cushioning arrangement **108** disclosed herein advantageously allow the cushioning arrangement **108** to include distended chambers **114a-114g**, **116a-116g** that are oriented at oblique angles and project beyond an outer periphery of the footbed and the upper **200**. The angled chambers **114a-114g**, **116a-116g** provide the sole structure **100** with an increased width to enhance stability along a lateral direction. Furthermore, orienting the walls of the chambers **114a-114g**, **116a-116g** at outward oblique angles allows lateral forces to be at least partially transmitted as axial forces (i.e., parallel to the walls) of the chambers **114a-114g**, **116a-116g** rather than as pure bending forces (i.e., transverse to the wall) to provide additional stability in the lateral direction. By forming the chamber cavities **1026**, **1028** of the mold system **1000** at different angles than the angles of the assembled chambers **114a-114g**, **116a-116g**, the chamber cavities **1026**, **1028** can be formed with positive

draft angles to allow easy extraction of the chambers **114a-114g**, **116a-116g** from the mold system **100**.

The following Clauses provide exemplary configurations for an article of footwear, a bladder for an article of footwear, or a sole structure for an article of footwear as well as related methods for forming an article of footwear, a bladder for an article of footwear, or a sole structure for an article of footwear described above.

Clause 1. A sole structure for an article of footwear, the sole structure comprising a chassis including a first side defining a footbed and a second side disposed on an opposite side from the first side, a first bladder attached to the second side of the chassis and including at least one first chamber defining a first polar axis oriented in a first direction, and a second bladder attached to second side of the chassis and including at least one second chamber defining a second polar axis oriented in a second direction transverse to the first direction.

Clause 2. The sole structure of Clause 1, wherein the first direction is a first oblique angle oriented towards a lateral side of the sole structure and the second direction is a second oblique angle oriented towards a medial side of the sole structure.

Clause 3. The sole structure of any of the preceding Clauses, wherein the at least one first chamber is aligned with the at least one second chamber in a lateral direction of the sole structure.

Clause 4. The sole structure of any of the preceding Clauses, wherein the at least one first chamber and the at least one second chamber each have an ellipsoidal shape.

Clause 5. The sole structure of Clause 4, wherein the ellipsoidal shape is truncated.

Clause 6. The sole structure of any of the preceding Clauses, wherein the at least one first chamber includes a plurality of first chambers arranged along a lateral side of the sole structure and the at least one second chamber includes a plurality of second chambers arranged along a medial side of the sole structure, each of the first chambers oriented in the first direction and each of the second chambers oriented in the second direction.

Clause 7. The sole structure of any of the preceding Clauses, wherein the second side of the chassis includes at least one first socket attached to the at least one first chamber and at least one second socket attached to the at least one second chamber.

Clause 8. The sole structure of Clause 7, wherein the at least one first socket is oriented in the first direction and the at least one second socket is oriented in the second direction.

Clause 9. The sole structure of Clause 7, wherein the at least one first socket includes a first receptacle configured to receive the at least one first chamber and the at least one second socket includes a second receptacle configured to receive the at least one second chamber.

Clause 10. The sole structure of Clause 9, wherein the first receptacle defines a first concave surface and the second receptacle defines a second concave surface.

Clause 11. The sole structure of any of the preceding Clauses, wherein the first bladder and the second bladder are a unitary piece.

Clause 12. The sole structure of any one of Clauses 1-10, wherein the first bladder and the second bladder are separate from one another.

Clause 13. A sole structure for an article of footwear, the sole structure comprising a chassis including a top side

defining a footbed and a bottom side disposed on an opposite side from the top side, a first bladder attached to the chassis at the bottom side and including at least one first chamber distended beyond the footbed on a first side of the sole structure, and a second bladder attached to the chassis at the bottom side and including at least one second chamber distended beyond the footbed on a second side of the sole structure. 5

Clause 14. The sole structure of Clause 13, wherein the at least one first chamber extends at a first oblique angle oriented towards the first side of the sole structure and the at least one second chamber extends at a second oblique angle oriented towards the second side of the sole structure. 10

Clause 15. The sole structure of any one of Clauses 13-14, wherein the at least one first chamber is aligned with the at least one second chamber in a lateral direction of the sole structure. 15

Clause 16. The sole structure of any one of Clauses 13-15, wherein the at least one first chamber and the at least one second chamber each have an ellipsoidal shape. 20

Clause 17. The sole structure of Clause 14, wherein the ellipsoidal shape is truncated.

Clause 18. The sole structure of any one of Clauses 13-17, wherein the at least one first chamber includes a plurality of first chambers arranged along a lateral side of the sole structure and the at least one second chamber includes a plurality of second chambers arranged along a medial side of the sole structure, each of the first chambers oriented in a first direction and each of the second chambers oriented in a second direction. 25

Clause 19. The sole structure of any one of Clauses 13-18, wherein the bottom side of the chassis includes at least one first socket attached to the at least one first chamber and at least one second socket attached to the at least one second chamber. 35

Clause 20. The sole structure of Clause 19, wherein the at least one first socket is oriented towards the first side of the sole structure and the at least one second socket is oriented towards the second side of the sole structure. 40

Clause 21. The sole structure of Clause 19, wherein the at least one first socket includes a first receptacle configured to receive the at least one first chamber and the second socket includes a second receptacle configured to receive the at least one second chamber. 45

Clause 22. The sole structure of Clause 21, wherein the first receptacle defines a first concave surface and the second receptacle defines a second concave surface.

Clause 23. The sole structure of any one of Clauses 13-22, wherein the first bladder and the second bladder are a unitary piece. 50

Clause 24. The sole structure of any one of Clauses 13-22, wherein the first bladder and the second bladder are separate from one another.

Clause 25. A method of forming a sole structure for an article of footwear, the method comprising inserting a barrier layer in a mold cavity of a mold assembly, the mold cavity defining at least one first chamber cavity oriented at a first angle and at least one second chamber cavity oriented at a second angle, biasing the barrier layer against a surface of the mold cavity to form a cushioning arrangement including at least one first chamber in the at least one first chamber cavity oriented at the first angle and at least one second chamber in the at least one second chamber cavity oriented at the second angle; extracting the cushioning arrangement from the mold cavity, rotating the first chamber in a first 55

direction about a longitudinal axis of the cushioning arrangement to orient the first chamber at a third angle, and rotating the second chamber in a second direction about the longitudinal axis to orient the second chamber at a fourth angle transverse to the third angle.

Clause 26. The method of Clause 25, further comprising attaching the first chamber to a first socket of a chassis oriented at the third angle and attaching the second chamber to a second socket of the chassis oriented at the fourth angle.

Clause 27. The method of Clauses 25 or 26, wherein orienting the at least one first chamber at the third angle includes positioning a lower portion of the at least one first chamber outwardly from an upper portion of the first chamber relative to a longitudinal axis of the sole structure.

Clause 28. The method of any one of Clauses 25-27, wherein the at least one first chamber cavity includes a plurality of first chamber cavities and the at least one second chamber cavity includes a plurality of second chamber cavities.

Clause 29. The method of Clause 28, wherein biasing the barrier layer against the surface of the mold cavity includes providing a fluid to the plurality of first chamber cavities via a first inflation conduit and providing a fluid to the plurality of second chamber cavities via a second inflation conduit in parallel with the first inflation conduit.

Clause 30. The method of any one of Clauses 25-29, further comprising joining the barrier layers together at a first inflation port to seal the at least one first chamber and joining the barrier layers together at a second inflation port to seal the at least one second chamber in fluid isolation from the at least one first chamber.

Clause 31. The method of any one of Clauses 25-30, wherein the mold cavity defines a ridge disposed between the at least one first chamber cavity and the at least one second chamber cavity.

Clause 32. The method of Clause 31, wherein the ridge includes a first ridge surface adjacent to the at least one first chamber cavity and a second ridge surface adjacent to the at least one second chamber cavity, the first ridge surface being transverse to the second ridge surface.

Clause 33. The method of Clause 31, wherein a width of the ridge tapers between the first chamber cavity and the second chamber cavity.

Clause 34. The method of any one of Clauses 31-33, further comprising forming a gap between the at least one first chamber and the at least one second chamber using the ridge, and bending the at least one first chamber towards the at least one second chamber to reduce a width of the gap.

Clause 35. A mold system for forming a cushioning arrangement for an article of footwear, the system comprising at least one first chamber cavity oriented at a first angle, at least one second chamber cavity oriented at a second angle transverse to the first angle, an inflation manifold including a first inflation conduit in fluid communication with the at least one first chamber cavity and a second inflation conduit in fluid communication with the at least one second chamber cavity.

Clause 36. The system of Clause 35, wherein the at least one first chamber cavity includes a plurality of chamber cavities fluidly coupled along the first inflation conduit and the at least one second chamber cavity includes a plurality of second chamber cavities fluidly coupled along the second inflation conduit.

21

Clause 37. The system of Clauses 35 or 36, wherein the at least one first chamber cavity has a first ellipsoidal shape defining a first axis oriented at the first angle and the at least one second chamber cavity has a second ellipsoidal shape defining a second axis oriented at the second angle.

Clause 38. The system of Clause 37, wherein at least one of the first ellipsoidal shape or the second ellipsoidal shape is a truncated ellipsoidal shape.

Clause 39. The system of any one of Clauses 35-38, further comprising a ridge disposed between the at least one first chamber cavity and the at least one second chamber cavity.

Clause 40. The system of Clause 39, wherein the ridge includes a first ridge surface adjacent to the at least one first chamber cavity and a second ridge surface adjacent to the at least one second chamber cavity, the first ridge surface transverse to the second ridge surface.

Clause 41. The system of Clause 39, wherein a width of the ridge tapers between the first chamber cavity and the second chamber cavity.

The foregoing description has been provided for purposes of illustration and description. It is not intended to be exhaustive or to limit the disclosure. Individual elements or features of a particular configuration are generally not limited to that particular configuration, but, where applicable, are interchangeable and can be used in a selected configuration, even if not specifically shown or described. The same may also be varied in many ways. Such variations are not to be regarded as a departure from the disclosure, and all such modifications are intended to be included within the scope of the disclosure.

What is claimed is:

1. A sole structure for an article of footwear, the sole structure comprising:
  - a chassis including a first side defining a footbed and a second side disposed on an opposite side from the first side, the chassis extending across a width of the sole structure from a medial side to a lateral side and from a forefoot region to a heel region;
  - a first bladder attached to the second side of the chassis and including a plurality of first chambers arranged along the lateral side of the sole structure, the plurality of first chambers each (i) defining a first polar axis oriented in a first direction and (ii) including a generally hemispherical first upper chamber wall;
  - a second bladder attached to the second side of the chassis and including a plurality of second chambers arranged along the medial side of the sole structure, the plurality of second chambers each (i) defining a second polar axis oriented in a second direction transverse to the first direction and (ii) including a generally hemispherical second upper chamber wall; and
  - a web disposed between the first bladder and the second bladder and extending continuously between the medial side of the sole structure and the lateral side of the sole structure and along a longitudinal axis of the sole structure.
2. The sole structure of claim 1, wherein the first direction is a first oblique angle oriented towards the lateral side of the sole structure and the second direction is a second oblique angle oriented towards the medial side of the sole structure.
3. The sole structure of claim 1, wherein first chambers of the plurality of first chambers are aligned with second chambers of the plurality of second chambers in a lateral direction of the sole structure.

22

4. The sole structure of claim 1, wherein each first chamber of the plurality of first chambers and each second chamber of the plurality of second chambers has an ellipsoidal shape.

5. The sole structure of claim 4, wherein the ellipsoidal shape is truncated.

6. The sole structure of claim 1, wherein the second side of the chassis includes a plurality of first sockets, each first socket attached to a respective first chamber of the plurality of first chambers, and a plurality of second sockets, each second socket attached to a respective second chamber of the plurality of second chambers.

7. The sole structure of claim 6, wherein first sockets of the plurality of first sockets are oriented in the first direction and second sockets of the plurality of second sockets are oriented in the second direction.

8. The sole structure of claim 6, wherein each first socket of the plurality of first sockets includes a first receptacle configured to receive a respective first chamber of the plurality of first chambers and each second socket of the plurality of second sockets includes a second receptacle configured to receive a respective second chamber of the plurality of second chambers.

9. The sole structure of claim 8, wherein the first receptacle defines a first concave surface and the second receptacle defines a second concave surface.

10. A sole structure for an article of footwear, the sole structure comprising:

- a chassis including a top side defining a footbed and a bottom side disposed on an opposite side from the top side, the chassis extending across a width of the sole structure from a medial side to a lateral side and from a forefoot region to a heel region;
- a first bladder attached to the chassis at the bottom side and including a plurality of first chambers arranged along the lateral side of the sole structure, the plurality of first chambers (i) distended beyond the footbed on the lateral side of the sole structure and (ii) each including a generally hemispherical first upper chamber wall;
- a second bladder attached to the chassis at the bottom side and including a plurality of second chambers arranged along the medial side of the sole structure, the plurality of second chambers (i) distended beyond the footbed on the medial side of the sole structure and (ii) including a generally hemispherical second upper chamber wall; and
- a web disposed between the first bladder and the second bladder and extending continuously between the medial side of the sole structure and the lateral side of the sole structure and along a longitudinal axis of the sole structure.

11. The sole structure of claim 10, wherein first chambers of the plurality of first chambers extend at a first oblique angle oriented towards the lateral side of the sole structure and second chambers of the plurality of second chambers extend at a second oblique angle oriented towards the medial side of the sole structure.

12. The sole structure of claim 10, wherein first chambers of the plurality of first chambers are aligned with second chambers of the plurality of second chambers in a lateral direction of the sole structure.

13. The sole structure of claim 10, wherein each first chamber of the plurality of first chambers and each second chamber of the plurality of second chambers has an ellipsoidal shape.

14. The sole structure of claim **13**, wherein the ellipsoidal shape is truncated.

15. The sole structure of claim **10**, wherein the bottom side of the chassis includes a plurality of first sockets, each first socket attached to a respective first chamber of the plurality of first chambers and a plurality of second sockets, each second socket attached to a respective second chamber of the plurality of second chambers. 5

16. The sole structure of claim **15**, wherein first sockets of the plurality of first sockets are oriented towards the lateral side of the sole structure and second sockets of the plurality of second sockets are oriented towards the medial side of the sole structure. 10

17. The sole structure of claim **15**, wherein each first socket of the plurality of first sockets includes a first receptacle configured to receive a respective first chamber of the plurality of first chambers and each second socket of the plurality of second sockets includes a second receptacle configured to receive a respective second chamber of the plurality of second chambers. 15 20

18. The sole structure of claim **17**, wherein the first receptacle defines a first concave surface and the second receptacle defines a second concave surface.

* * * * *
